(57) **CLAIM**

The ornamental design for an implant abutment, as shown and described.

DESCRIPTION

FIG. 1 is a bottom and front perspective view of an implant abutment showing our new design;

FIG. 2 is a front elevation thereof;

FIG. 3 is a bottom plan view thereof;

FIG. 4 is a right side elevation thereof; and,

FIG. 5 is a cross-sectional view taken along line 5-5 of FIG. 2.

The broken lines in FIGS. 1, 2 and 4 are included for the purpose of illustrating environmental structure and form no part of the claimed design.
